TELEGRAPH EXCHANGE SYSTEM

Ronald George Griffith, Croydon, England, assignor to Creed and Company, Limited, Croydon, England

Application May 5, 1932, Serial No. 609,419
In Great Britain December 11, 1931

18 Claims. (Cl. 178—2)

This invention relates to telegraph exchange systems generally, and more particularly to printing telegraph systems wherein any two of a plurality of subscribers or signalling stations can be connected together by switching operations effected manually at a central interconnecting station.

Although the novel features and mode of connections which form the subject matter of the present invention are not necessarily limited to manual exchange systems or to exchange systems for printing telegraphs, the actual example hereinafter described has been developed primarily in view of a manual exchange system for printing telegraph communication. The present arrangements may also be considered as an improvement of the system described in U. S. application No. 532,225 filed 23rd April 1931.

In this latter mentioned system signalling current is furnished by a source of energy situated at the central station and means is shown whereby distinctive calling and clearing signals can be transmitted from a subscriber's station to the central station over the subscriber's line circuit which circuit is also used for teleprinter communication.

In order to retain the advantages of the use of a polarized relay in printing telegraph receiving apparatus in such an exchange system, which relay would be suitably biased in the case whilst single current impulses are employed for teleprinter communication, and in order to avoid the necessity for repeating relays at the central station, it has been usual to provide separate jacks or equivalent terminal connections for each subscriber, one for effecting a connection to the subscriber's line circuit in response to a calling condition received from the subscriber and the other for effecting a connection to the subscriber's line circuit in response to another subscriber's request.

The object of the present invention is to provide a simplified system of connection for a telegraph exchange system affording all the advantages of the features already outlined and in which only a single line jack or equivalent terminal connection need be provided for each subscriber's line circuit.

Another object of the invention is to reduce the number of auxiliary circuit connections associated with a cord circuit for interconnecting any two subscribers, a single connecting wire sufficing for the communication circuit between two line jacks.

Another object is to provide alarm means at a central station responsive to any one of various

conditions which may have arisen to give indication to an operator to remove the plug of a cord circuit.

Another object of the invention is to provide an improved method of arranging for a single back-signalling means at a central station to be common to a plurality of cord circuits through a plurality of operators positions.

Yet another object is to arrange so that a central station operator can plug in to a required subscribers line jack without the necessity of previously testing the "busy" or "free" condition of this subscriber's station. For this purpose means is provided for identifying a particular cord circuit after the operator has plugged in, if a "busy" condition was encountered and no connection therefore effected by that cord circuit.

These and other objects of the invention are attained by the arrangements hereinafter described, will be evident from the example hereinafter described in detail of the mode in which these objects are attained, the invention consisting in the combinations and sub-combinations more particularly defined in the appended claims.

In the drawings, Fig. 1 shows a diagram of connections at a subscriber's station, Fig. 2 shows the terminal connection for a subscriber at a central station and Figs. 3, 4 and 5, each figure being delimited by chain lines indicated on sheets 2 and 3, show the arrangements and connections at the central station, Fig. 3 showing a cord circuit, Fig. 4 an operator's position which may be common to a plurality of cord circuits, and Fig. 5 the auxiliary and like signalling apparatus which may be common to the whole central station.

It will be understood that in these drawings and for the purpose of the following description, Fig. 3 is supposed to adjoin Fig. 2. In the description also, as the various parts referred to therein are mainly located at the central station shown as a whole in Sheets 2 and 3 of the drawings, it is not thought to be necessary to refer to each individual figure for the location of detail parts.

1. *A subscriber calling the exchange*

To call the exchange the subscriber depresses his calling key CFK, thus earthing the loop and energizing his calling relay A at the exchange through the following circuit:

Earth, resistance R1 to midpoint of teleprinter relay windings, thence via both sides of the loop

to contacts B3 and B4, normal, via contacts A1, normal, to the battery winding of relay A.

In operating, relay A energizes its relief relay AA via A2, operated, and locks itself in its 5 operated condition via its earthed winding and A1, operated.

The current that traverses this circuit will be in such a direction as to hold the armature of the teleprinter polar magnet to the "space" side.

10 Relay AA in operating lights the calling lamp CL on each operator's position, via B1, normal, AA3, operated, and at night time, if desired, sounds an audible alarm by means of relay NA, operated via B2 normal, AA4 operated.

15 The calling relief relay AA also prepares a locking circuit for itself at contacts AA5, operated, and prepares the "Exchange answering" circuit for the calling subscriber via AA1, AA2, operated, to the negative pole of the signalling 20 battery SB and the tip connection of LJ, respectively.

2. The exchange answering the calling subscriber

Observing a calling lamp CL glowing on their 25 position, any idle operators will insert an answering plug AP of a connecting cord into the line jack LJ of the glowing calling lamp. The operator whose plug first establishes the "ring" connection seizes the call, and all other operators 30 who have answered the call will receive the "Bar" alarm (subsequently described in paragraph 19), notifying them to withdraw.

When the operator seizes a call the "cut off" relay B and cord relay CC are energized in series 35 through the following circuit:

Battery, winding of relay B ring connections of LJ and AP, via L6 normal operating winding of relay CC to earth.

When operated relay CC energizes "display 40 pick up" relay C via contacts CC1 and prepares a locking circuit for itself at contacts CC2 which is completed on the operation of relay E. By the closing of contacts CC3 a circuit for relay J is prepared.

45 In operating, relay B applies a locking potential to the winding of relay AA at B2 and extinguishes the calling lamp CL at B1. It also "busies" the line jack LJ (if multiplied) by applying earth potential to the sleeve connection via B5, and transfers one side of the loop from the calling relay A to the tip connection of LJ via contacts B3, AA2 operated and the other side to battery via contacts B4, AA1, operated. The operation of relay B releases relay A which 55 stores to normal.

3. Calling subscriber given indication when to dial

The operation of relay C closes the circuit of the Telex transmitter "Motor Start" relay MS at 60 C3 and connects the impulsing relay D of the display equipment to the calling subscriber, establishing the following circuit:

Earth, contacts G2, normal, winding of relay D, contacts C1, operated, L5, normal, tip connections of AP and LJ, contacts AA2, B3, operated, via the loop, subscriber's equipment and a balancing resistance R, contacts B4, AA1, operated, via a protective resistance PR to the signalling battery SB.

70 The direction of current through the loop has now been reversed thus causing the armature of the teleprinter polar magnet to move to the "mark" side, which by tripping the "crawling" device, effects the automatic starting of the teleprinter motor.

The contacts of the "crawling" device are so arranged that contacts CD1, CD2 are closed before contacts CD3, CD4 are opened; contacts CD5, CD6 are then closed completing the motor circuit.

This current is also of such a magnitude as to operate the subscriber's indicator SI causing it to display the letters "Dial". The calling subscriber is thus given indication that he can dial the number of the wanted subscriber.

80 Relay D in operating completes an energizing circuit for relay E at D1. Relay E when operated lights the display pilot lamp DPL and removes earth from the "homing wiper" W1 of the digit switch DS at E3, and prepares a circuit for the "digit switch" relay F at E2.

4. The calling subscriber giving the number of the wanted subscriber

85 In order to display the wanted number the subscriber has to transmit by means of his dial four groups of impulses which are reproduced on relay D. Relay E being slow to release holds its contacts closed during the impulsion of contacts D1.

90 To prevent the teleprinter polar magnet from responding to the dialling impulses a resistance R2 is shunted across the contacts DU of the dial permitting a holding current to flow through the 105 windings of the teleprinter polar magnet to hold the armature to the "mark" side. This current, however, is not sufficient to appreciably effect the impulsion of relay D.

95 The first group of "dial impulses" operates the first "numerical switch" driving magnet DM1 through the following circuit:

Earth, contacts D1, impulsion, contacts E2, operated, winding of relay F, via the wiper W2 and the first contact position of the digit switch 115 DS, winding of DM1 to battery.

120 The first group of dial impulses causes the wipers of the first numerical switch NS1 to be stepped round to a position determined by the number dialled. The driving magnets are arranged to step the wipers round over one contact each time they are de-energized.

125 The first group of dial impulses through relay F causes it to operate and energize via contacts G1, normal contacts F1, operated, the "digit switch" driving magnet DMD.

130 At the termination of the first group of impulses, representing the first number, relay D and relay E remain energized and therefore relay F is de-energized, which in turn de-energizes the "digit switch" driving magnet DMD thus causing its contact wipers to be stepped on to their next contact.

135 At the same time the lamp corresponding to the number dialled for the first digit is lighted via contacts G1, F1, normal, wiper W3 and second contact position of the digit switch DS, wiper W3 of the first numerical switch NS1, via the selected lamp to battery.

140 When the subscriber dials the second numeral, relay F is energized in series with the driving magnet DM2 of the second numerical switch NS2 via the second contact position of wiper W2 of the digit switch DS. The driving magnet DM2 is thus energized and de-energized a number of 145 times equivalent to the numeral dialled, stepping its wipers through a corresponding number of divisions.

150 At the termination of the second group of impulses relays D and E again remain energized and

relay F is again deenergized causing the driving magnet DMD to again become deenergized and step its wipers on to their third contact position. The second numeral is displayed by the following circuit:

Contacts G1, F1, normal, wiper W3 and the third contact position of DS, via wiper W3 of NS2 to battery through the selected lamp. The lamp selected for the first numeral is now kept 10 alight by earth being put back from wiper W2 of NS2.

The display of the remaining two digits is effected in an identical manner, the second and third digit lamps maintaining their earth connection via wiper W2 of NS3 and NS4 respectively and the fourth digit lamp, via contacts G1, F1, normal, wiper W3 and the fifth contact position of the digit switch DS.

Thus the number dialled by the calling subscriber is displayed to the exchange operator.

5. The exchange operator establishing connection with the wanted subscriber

Having observed the number displayed the exchange operator inserts into the appropriate line jack LJ the calling plug CP of the connecting cord in use. The insertion of the calling plug, energizes relays H and B in series through the following circuit:

30 Earth, operating winding of relay H, ring connections of CP and LJ, winding of relay B to battery.

The operations of relay H lights the supervisory lamp SL via contacts P2, M1, normal, contacts H1, operated. It also applies a holding potential to relay MS at contacts H4. Relay H will not operate if the line is engaged.

The operation of relay B connects the wanted subscriber's equipment to the cord circuit and establishes the following circuit:

35 Earth, contacts AA2, normal, contacts B3, operated, via the loop, subscriber's equipment, and a balancing resistance R; contacts B4, operated, AA1, normal, tip connections of LJ and CP, contacts H3, operated, winding of supervisory relay J, contacts O4, normal, via a current limiting resistance R5 to signalling battery SB.

When current traverses this current it causes the armature of the teleprinter polar relay to move to the "mark" side, which by tripping the "crawling" device effects the automatic starting of the teleprinter motor.

The supervisory relay J is also operated and energizes relay K via contacts J1, which in operating energizes relay L via contacts K1.

The operation of relay L releases the display equipment from the cord circuit by opening the back contacts of L5 and L6. The closing of the front contact of L5 maintains earth on the calling subscriber's loop via contacts P1, O5, N4 normal; and that of L6 completes a locking circuit for relay L via the ring connections of AP and LJ and the winding of relay B. It also completes a locking circuit for relay H at L4 and an energizing circuit for relay M at L3. Relay M in operating accomplishes the following:

(a) Extinguishes the supervisory lamp SL by opening contacts M1.

70 (b) Locks itself in its operated condition via contacts H1, M1, operated.

(c) Prepares an energizing circuit for the "line cut-off" relay P at contacts M2.

(d) Prepares an energizing circuit for relay N at contacts M3.

(e) Prepares an energizing circuit for relay O at contacts M4.

The first time therefore that contacts P.U.C. are closed after the operation of relay M, "pick-up" relay N will be energized via O3 normal, M3, operated, and when operated, will lock itself in its operated condition via contacts N1 and the break contacts of T.O.C. to earth.

In this condition relay N connects the "Thru" transmission contacts TT of the telex transmitter, to the calling subscriber via contacts X2, S1, normal, N4, operated, resistance R4, contacts O5, P1, normal, resistance R3, contacts L5, operated, and the tip connections of AP and LJ.

6. The calling subscriber given indication that the connection has been established

Teleprinter impulses are now transmitted from contacts TT via the above circuit, causing the letters "Thru" to be printed on the calling subscriber's teleprinter giving him indication that connection has been established with the wanted subscriber.

7. The exchange operator given indication that the connection has been established

Upon the operation of relay N, and therefore, during the transmission of the letters "Thru", the transmission lamp TL is lighted via contacts N3, giving the operator indication that the connection has been established and that the letters "Thru" are being transmitted.

8. Extending the call to the wanted subscriber

The cams of the telex transmitter are so orientated that upon the completion of the transmission of the letters "Thru", the make contacts of TOC of the telex transmitter are closed energizing relay O via N2, operated, O6, normal, M4, operated, which when operated locks itself via contacts M4, O6, M5, operated.

With the opening of the break contacts of TOC the locking circuit of relay N (slow release) is opened, which restores its contacts to normal after a short period allowing sufficient time for the operation of relay O.

Relay O in operating accomplishes the following:

(a) Completes the connection together of the calling and wanted subscribers at the front contacts of O5.

(b) Removes the signalling battery from the wanted subscriber's equipment by opening contacts O4.

(c) Completes a locking circuit for itself at O6 as mentioned above.

(d) Interrupts the operating circuit of relay N for that particular cord circuit at O3.

(e) Removes earth from the "motor start" relay MS at O1 which will become de-energized unless held energized by another cord circuit.

Upon the extension of the call to the wanted subscriber the completed circuit will be as follows:

Negative pole of signalling battery SB, protective resistance PR, contacts AA1, B4, operated, balancing resistance R, via the loop and calling subscriber's equipment, contacts B3, AA2, operated, tip connections of LJ and AP, contacts L5, operated, resistance R3, contacts P1, normal, O5, operated, winding of supervisory relay J, contacts H3, operated, tip connections of CP and LJ, contacts AA1, normal, B4, operated, balancing resistance R via the loop and the wanted subscriber's equipment, contacts B3, operated, and AA2, normal, to earth.

The direction of current through this circuit is such that the armatures of both teleprinter polar magnets are held to the "mark" side.

5. The calling subscriber verifying exchange connection

After receiving indication that the connection is completed a subscriber can verify the exchange connection by depressing his "Who are you" key, 10 which effects the release of mechanism in the connected teleprinter, causing it to transmit back its exchange number. Thus, having ascertained that he is connected with the desired number, the subscriber transmits his message.

15. 10. Automatic release of the exchange display equipment from the cord circuit

Upon the operation of relay L as outlined in paragraph 5, the back contacts of L5 and L6 are 20 opened interrupting the energizing circuits of relays D and CC respectively. Relay D when de-energized, de-energizes relay E thus interrupting the locking winding of relay CC, which when de-energized opens the energizing circuit of the 25 "display pick up" relay C restoring it to normal. The display equipment is thus released from the cord circuit.

The energizing circuit of relay B is now retained via the front contact of L6 and the locking winding of relay L. Relay H is thus held energized via circuits of both the answering and calling plugs AP and CP, and therefore cannot become de-energized until both plugs have been removed. This ensures that the supervisory lamp 35 SL will remain alight after the clearing of a connection, as will be detailed later, until both plugs have been withdrawn.

11. Resetting of the display equipment

40 Relay D, when de-energized restores contacts D1 to normal, interrupting the circuit of relay E which also becomes de-energized extinguishing the "display pilot" lamp DPL by restoring contacts E3 to normal, and applies earth potential 45 via the break contacts of E3 and winding of relay G to the "homing wiper" W1 of the "digit switch" DS. The driving magnet DMD is energized and upon operating opens its own contacts causing it to become de-energized and thereby 50 rotate the wipers on to the next contact. The driving magnet contacts are now again closed and therefore the driving magnet is again energized repeating the above cycle of operations. This continues until wiper W1 reaches its "normal" contact where it passes the earth potential 55 on to the "homing wiper" W1 of NS1. This in turn "homes" in the same manner and places the resetting potential on to the "homing wiper" W1 of NS2 and so on until all the switches have 60 reached their normal position.

During this period "resetting" relay G is energized and in its operated condition opens the circuit of impulsing relay D at contacts G2 and removes earth potential from the display lamps 65 at G1.

12. The exchange operator receiving indication when connection is disengaged

Having completed transmission either subscriber can clear the connection at the exchange and light the supervisory lamp SL in the following manner:

The depression of the clearing key CK for a short period de-energizes the "supervisory" relay 75 J which on restoring its contacts to normal de-

energizes relay K. The "line cut-off" relay P is then energized via contacts K1, normal, M2, operated and when operated lights the supervisory lamp SL and the position pilot lamp PPL via contacts P2, P3, respectively.

With the operation of relay P the line circuit is broken at contacts P1. These contacts will remain open until the release of relay P upon the withdrawal of both the answering and calling plugs from their respective jacks.

13. The exchange operator breaking down connection at the exchange

Observing the "supervisory" lamp SL and "position pilot" lamp PPL, glowing, the exchange operator breaks down the connection by removing both the answering and calling plugs from their respective jacks. The withdrawal of the plugs de-energizes relays H and L causing relays M, O and P also to become de-energized and thus restore the cord circuit to its idle condition.

The de-energizing of relay P extinguishes the supervisory lamp SL and the position pilot lamp PP1 by opening contact P2 and P3. As explained in paragraph 10 the supervisory lamp SL will not be extinguished until both plugs have been withdrawn.

14. Automatic clearing of the exchange connection

To prevent a subscriber holding the line engaged indefinitely after he has concluded the transmission of his message, a "crawling" device CD is incorporated in the teleprinter whereby the call will be automatically cleared after an idle 110 line period of approximately three minutes, by the opening of contacts CD1, CD2, just prior to the closing of contacts CD3, CD4, in readiness for the next call. Contacts CD5, CD6, are then opened interrupting the motor circuit.

The opening of contacts CD1, CD2 effects the clearing of the connection at the exchange in an identical manner as when the clearing key CK is depressed by a subscriber.

15. The calling subscriber given indication that the wanted subscriber is engaged

If the exchange operator is asked for a number that is already engaged, the insertion of the calling plug CP into the line jack LJ will effect 125 the printing of the letters "Busy" on the calling subscriber's teleprinter in the following manner:

It is arranged that no two H relays can operate in parallel, therefore on the insertion of CP into LJ relay R will operate due to earth potential being on the sleeve connection of the jack and contacts H2 being normal.

Relay R in operating closes an energizing circuit for the "switching" relay S at R4 and for relay J at R3. When operated relay S prepares a circuit for the transmission of the letters "Busy" at contacts S1 lights the engaged lamp EL at contacts S2 and maintains relay MS energized via contacts S3.

With the operation of relay J relays K, L, M, N are operated and maintained in a manner identical to that explained in paragraph 5, except that the locking circuit of relay M is now maintained via contacts H1, normal, R5, M1, operated.

Immediately after the operation of relay N, teleprinter impulses are transmitted from contacts BT of the telex transmitter via contacts S1, operated, causing the letters "Busy" to be printed on the calling subscriber's teleprinter.

During this period the transmission lamp TL is lighted via contacts N3 operated.

16. The exchange operator given indication that the letters "Busy" have been transmitted

At the conclusion of the transmission of the letters "Busy" relay O is energized, operated and locked in the same manner as after the transmission of the letters "Thru". When operated it interrupts the energizing circuits of relays S, J and N at contacts O1, O2, O3, respectively. Relay J when de-energized, opens the energizing circuit of relay K at contacts J1, de-energizing it. Contacts K1 are restored to normal, effecting the energizing of relay P via contacts K1, normal, M2, operated, which when operated lights the "supervisory" lamp SL at P2, and the "Position pilot" lamp PPL at P3, giving the operator indication that the transmission of the letters "Busy" is completed and that she may withdraw the plugs.

As before, the "supervisory" lamp will not be extinguished until both plugs have been withdrawn, the de-energizing of relay P being dependent on relay M, which cannot now restore to normal until relays R and L are de-energized.

17. The exchange operator testing for disengaged lines

If a subscriber has more than one line it is desirable that the operator shall be able to test all lines for "Busy" before notifying the calling subscriber that the number is engaged.

An engaged test key ETK is therefore provided which when depressed interrupts the energizing circuit of the "supervisory" relay J, so that if the calling plug CP is inserted into the multiple of a line jack which is already engaged the "engaged" lamp EL will light on the operation of relays R and S but the letters "Busy" will not be transmitted to the calling subscriber owing to relays J, K, L, M and N not being operated.

If a disengaged line is found relay H will operate, interrupting the circuit of relay R at H2, preventing the lighting of the engaged lamp EL and the call is extended to the wanted subscriber in the normal manner.

If, however, after testing all the lines of a subscriber and finding them all engaged, she will leave the plug in the last jack tried and on the release of the engaged test key ETK the letters "Busy" will be transmitted in the manner described in paragraph 15.

18. The exchange operator transmitting "Busy" when it is not convenient to insert the calling plug into a line jack

If, for any reason, it is not convenient to insert the calling plug into the line jack of a wanted subscriber, whose line or lines are engaged, the exchange operator can transmit the letters "Busy" to the calling subscriber by inserting the calling plug into a special jack that has earth potential connected to its sleeve connection. The insertion of the plug will therefore effect the transmission of the letters "Busy" in an identical manner to that when a plug is inserted into the multiple of an engaged jack.

19. "Bar" alarm

An alarm has been provided on each position to give indication to an operator when she has to withdraw a plug from the multiple field for any reason except that of breaking down a connection at the completion of a conversation.

These may be as follows:

Reason:—(a) Several operators answering an incoming call.

Result:—Only "display pick-up" relay C and consequently position relay E of the operator who has seized the call will operate opening contacts E1. Relay V on all other positions will therefore be energized as follows:

Earth, contacts B5, operated, sleeve connections of LJ and AP, contacts L1, E1, U1, normal, winding of relay V to battery.

Relay V in operating closes an energizing circuit for relay T at contacts V2 which when operated energizes relay U by closing contacts T1. Relay U when operated locks relay T operated, via contacts U2, and breaks the energizing circuit of relay V at U1, preparing an energizing circuit for the "Bar" alarm at the same contacts.

When relay V restores to normal it will close the energizing circuit for the "Bar" alarm via contacts V1 normal, U1 operated, E1, L1, normal, to earth on the sleeve connection of LJ.

The alarm will therefore sound until the plug is removed.

Reason:—(b) Answering plug inserted into the line jack of a subscriber who has not called the exchange.

Result:—The insertion of the plug will operate relays B, CC and C.

Reason:—(c) Answering plug inserted into the line jack of a subscriber who has been called.

Result:—On the insertion of the plug relay CC will fail to operate being in parallel with an H relay.

Reason:—(d) Calling plug inserted into a line jack of a subscriber who has just originated a call.

Result:—On the insertion of the calling plug relays H and B will be energized in series. Relay AA having been operated by the subscriber originating the call, relay J will fail to operate due to the same potential being applied to both ends of its winding, via contacts AA1 AA2 operated, contacts O4 normal. Relay V will therefore be energized via contacts H2 operated L2 normal, and the alarm will be sounded as described in (a). In this case, however, the operator will remove the plug and re-insert it immediately as the removal of the plug will annul the call originated by releasing relay B which when de-energized will restore relay AA to normal leaving the subscriber's equipment in a condition to be called.

20. A subscriber obtaining teleprinter connection with the exchange

After having called the exchange and having been answered the subscriber by dialling the figure O will release a train of impulses that will effect the lighting of the lamp corresponding to O on the "thousands" digit display.

On observing this indication the operator will insert the calling plug of the connecting cord in use into the monitor's jack, extending the call to the monitor's position in the normal manner.

21. A subscriber clearing a call before the exchange operator has answered

Should a subscriber after having called the exchange by depressing his calling key CFK, and before his indicator SI displays the letters Dial, decide that he does not wish to complete the call, he can extinguish his calling lamp at the exchange by depressing his clearing key CK, thus interrupting the circuit of relay A, causing contacts A1 A2 to restore to normal, breaking the

circuit of relay A at A1 and of relay AA at A2. Relay AA restoring to normal extinguishes the calling lamp CL.

5 22. A subscriber clearing a call due to mis-dialling

Should a subscriber make a mistake whilst dialling he will depress his clearing key CK and thus interrupt the energizing circuit of the impulsing relay D for a sufficient length of time to allow relay E to restore to normal.

10 Relay E when de-energized operates the "Bar" alarm via contacts E1, L1, normal, and applies earth potential to the "homing wiper" W1 of the "digit switch" via contacts E3 normal and the 15 winding of relay G, as explained above in paragraph 11, and the switches will be returned to normal. Relay G being energized, operates and locks itself via contacts D1, E2, normal, C2, G3, operated, and removes earth potential from the 20 impulsing relay D at contacts G2, so that the calling subscriber cannot effect the operation of this relay by further dialling.

Hearing the "Bar" alarm the operator will remove the calling plug de-energizing relays B and C.

25 When de-energized relay C interrupts the locking circuit of relay G at contacts C2, which when de-energized re-connects earth again to the impulsing relay D at contacts G2.

30 The calling subscriber can now re-call the exchange by depressing his calling key CFK as described in paragraph 1.

23. The calling subscriber given indication that the wanted subscriber's line is out of order

35 If an operator is asked for a subscriber whose line is out of order, she will insert the calling plug C P into the "out of order" jack OJ thereby effecting the automatic transmission of the 40 letters "Faulty" to the calling subscriber in the following manner.

45 The insertion of plug C P into jack OJ energizes relays W and H in series, but owing to the high resistance of relay W relay H will not operate.

The operation of relay W applies earth potential to the sleeve connections of O J and C P at contacts W1, operated, thereby completing a circuit for relay R via contacts H2 normal.

50 When operated relay W also completes an energizing circuit for relay X at contacts W2, operated, and prepares an energizing circuit for relay Z at contacts W3, operated.

55 Relay X when operated interrupts the energizing circuit of relay S at contacts X1 operated, prepares a circuit at contacts X2, operated, for the transmission of the letters "Faulty" from contacts FT of the telex transmitter, and lights the "out of order" lamp OL at X5.

60 The operation of relay R effects the operation of relays J, K, L, M, and N as described in paragraph 15, and subsequent to the operation of relay N the letters "Faulty" are automatically transmitted to the calling subscriber from contacts FT of the telex transmitter, via contacts X2, operated, S1, normal, N4, operated, O5, P1, normal, L5 operated.

Upon the completion of the transmission of the letters "Faulty" the make contacts of TOC 70 are closed applying earth potential to relay Z via contacts N2, X3, operated, and to relay O via contacts N2, operated, O6, normal, M4, operated.

75 Relay O in operating locks itself in its operated condition via contacts M5, O6, M4, oper-

ated, and effects the subsequent operations as described in paragraph 16.

Relay Z when operated locks itself in this condition via contacts W3, Z2, operated, and 80 interrupts the energizing circuit of relay X at contacts Z1, operated.

Relay X when de-energized restores its contacts to normal extinguishing the "out of order" lamp OL, notifying the completion of the transmission of the letters "Faulty".

The operator observing the "supervisory" and "position pilot" lamps glowing will remove the plugs from the jacks and so restore the cord circuit relays, and relays W and Z to normal.

85 24. AUTOMATIC INDICATION OF FAULTS

(a) *Earthed lines*

The permanent glow of a calling lamp CL would in most cases indicate that the line connecting the subscriber with the exchange is faulty to earth.

90 (b) *Disconnected lines*

The line is automatically tested whenever the exchange operator inserts a calling plug to call a subscriber. If the line has a disconnection fault the supervisory lamp SL will glow and the number of the wanted subscriber will remain displayed, thereby giving the operator indication that the line is disconnected.

95 25. *Indication of switching faults during connection*

100 By the lighting of the "display pilot" lamp DPL the exchange operator is given indication that her display equipment is connected to the calling subscriber.

If for any reason the display equipment is not 115 seized by the calling subscriber the "Bar" alarm will operate. If the normal functions are not completed to establish the transmission of "Thru" or "Busy", after the exchange operator has inserted a calling plug to complete connection, the "Bar" alarm operates.

If the switching out of the transmission of "Thru" or "Busy" is not effected indication is given to the exchange operator by the permanent glow of either the "Thru" or the "Engaged" 125 transmission lamp.

As the switching out of the transmission of "Thru" or "Busy" is the last switching function of the cord circuit when making connection, there is no need for any further indication and the 130 "position pilot" lamp covers the possibility of burnt out supervisory lamps.

135 26. *Testing connecting cords*

To enable an operator to test doubtful cords before reporting them as faulty two "dummy" subscriber's circuits terminating on two jacks DJ₁ DJ₂ are provided, the circuits being arranged to represent a calling and a wanted subscriber, respectively.

To test a cord the operator will insert the answering plug into the jack DJ₁. If the plug and associated cord is satisfactory the display pilot lamp DPL will glow. Upon the inserting of the 145 calling plug into jack DJ₂, if also satisfactory the lamp DPL will be extinguished and the transmission lamp TL lighted for a short period.

If either lamp fails to light then the cord 150 will be reported as faulty.

27. Calling subscriber requested to re-dial the number of the wanted subscriber

If, for any reason, an operator's display equipment is out of order, so that she fails to receive the dialled number correctly, she will, by depressing her "Re-dial" key Re-D.K. effect the automatic transmission in the following manner, of a signal requesting the calling subscriber to re-dial the number of the wanted subscriber.

The depression of key Re-D for a predetermined period prepares an energizing circuit for relay Y which is completed upon the next closure of contacts P.U.C., thus effecting its operation. Relay Y, when operated, lights the lamp Re-D.L. via contacts Y3 completes a locking circuit for itself from contacts T.O.C. of the telex transmitter via contacts Y2, and a transmitting circuit for the re-dialling signal from contacts Re-D.T. of the telex transmitter via resistance R11, contacts Y1, operated, YY1, L5, normal, tip connections of AP and LJ to the calling subscriber's teleprinter.

Upon the completion of this circuit, teleprinter impulses will be transmitted from contacts Re-D.T. effecting the printing of the letters "Re-dial" on the calling subscriber's teleprinter.

At the conclusion of the transmission, the locking winding of relay Y is interrupted by the opening of the break contacts of T.O.C. and when de-energized extinguishes lamp Re-D.L., indicating to the exchange operator that the transmission is completed.

Upon the extinction of the lamp re-D.L., the operator will throw her position change-over key, thus connecting the subscriber to her spare position set and causing the subscriber's indicator to display again the letters dial, informing him that he is in a position to re-dial the number of the wanted subscriber.

46 28. Calling subscriber requested to re-call the exchange

An operator, upon plugging in a calling plug to call a subscriber and finding that the call is not extended due to either position or cord relay trouble, will request the calling subscriber to re-call the exchange.

To accomplish this, she will depress her "re-call" key re-CK for a predetermined period, effecting the energizing and operation of relay YY upon the next closure of contacts P.U.C. of the telex transmitter. When operated relay YY lights the lamp re-C.L. via contacts YY5, completes a locking circuit for itself via contacts YY4, and prepares three circuits via contacts YY1, YY2, YY3 for the transmission of teleprinter impulses that will effect the printing of the letters "Re-call EX." on the calling subscriber's teleprinter.

The circuit traversed by these impulses will depend upon which relays have not been operated; viz:—

1. Relay L not operated

Via contacts re-C.T., resistance R12 contacts YY1 operated, L5, normal.

2. Relay N not operated

Via contacts re-C.T., contacts YY2 operated, N4, normal, resistance R4, contacts O5, P1, normal, contacts L5, operated.

3. Relay O not operated

Contacts Re-C.T., contact YY3, N4 operated, resistance R4, contacts O5, P1, normal, contacts L5, operated.

On completion of the transmission, the locking circuit of relay YY will be interrupted by the opening of the break contacts of T.O.C. which when de-energized extinguishes lamp re-C.L., giving the exchange operator intimation that the transmission is completed.

Observing the completion of the transmission, the exchange operator will remove the plugs from their respective jacks, throw her position key and upon the subscriber re-calling will connect him through to the wanted subscriber by means of another cord, and her spare position set.

She will then test the position apparatus by means of another cord and the "dummy" subscriber's jacks to ascertain whether the fault is in the position or cord circuits and will report accordingly.

29. Automatic operation of "who are you" device

During the establishment of a connection between two subscribers and coincident with the transmission of the letter "U" of the signal "Thru" the "Who are you" signal is transmitted to the wanted subscriber from contacts W.R.U. via contacts N5 M6, operated, O4, normal, winding of supervisory relay J, contacts H3, operated, to the wanted subscriber's equipment via the tip connections of CP and CJ.

At the completion of the transmission of "Thru" the call is automatically extended as described in paragraph 8, and mechanism is released in the wanted subscriber's teleprinter, due to the transmission of the "who are you" signal, which effects the transmission of its exchange number to the calling subscriber in a manner identical to that described in paragraph 9.

The calling subscriber is therefore automatically informed that he is connected through to another subscriber and is given the exchange number of that subscriber.

30. The connection together of two subscribers connected to different exchanges

To facilitate the connection together of two subscribers connected to different exchanges it can be arranged, for example on a four number display system for the thousands digit to be individual to each exchange and for the remaining three digits to be individual to the subscribers connected to the various exchanges.

With this arrangement a subscriber requiring connection with a subscriber connected to another exchange will, after having called his exchange, dial the number of the wanted subscriber and then wait until the letters "Thru" are printed on his machine as detailed in the foregoing pages when connection is effected between subscribers connected to the same exchange.

a. Exchange operator calling the distant exchange

Upon receipt of the number the exchange operator will depress her "trunking" key T.K. which by closing contacts T.K.3 will hold the number displayed by applying a holding potential to the impulsing relay D of the display equipment.

Then by inserting the calling plug C.P., of the connecting cord in use, into the tie line or junction jack of the exchange required she will call the distant exchange who will answer in the normal manner by inserting an answering plug into the answering jack of the glowing calling lamp.

b. Home exchange operator dialling out the required number

The insertion of the answering plug effects the

operation of the exchange indicator at the "home" exchange causing it to display the letters "Dial" giving the exchange operator indication that she is connected to the "distant" exchange 5 and can dial out the displayed number.

Still holding the "trunking" key depressed she will dial out by means of her dialling unit E.D.U. the number displayed on her display panel. This 10 number will be received and displayed at the distant exchange in a manner identical to that described in paragraph 4.

With the insertion of the answering plug by the distant exchange operator relay J of the home exchange cord circuit was energized and when 15 operated effected the operation of relays K, L, M as explained in paragraph 5.

Due to the operation of relay Q effected by the depression of the key T.K. and the closure of contacts T.K2, the energizing circuit of relay N 20 was interrupted at contacts Q1 to prevent the transmission of the letters "Thru" on the operation of relay O. Also by the closure of contacts Q2 an energizing circuit was prepared for relay O to be completed on the release of the key T.K.

25 *c. The calling subscriber extended to the distant exchange*

Having completed re-transmission of the number the exchange operator will release her key 30 T.K. and effect the energizing of relay O via contacts TK1, normal, Q2, operated, O6, normal, M4, operated. The opening of contacts TK2 de-energizes relay Q, but this relay being slow to release sufficient time elapses before its contacts 35 restore to normal to allow for the operation of relay O and the consequent connection together of the calling subscriber and the distant exchange.

With the opening of contacts TK3 relay D is de-energized effecting the resetting to normal of 40 the display equipment at the "home" exchange as described in paragraph 11.

The number of the wanted subscriber has thus been displayed at the distant exchange and the calling subscriber extended to that exchange 45 without the transmission of the letters "Thru".

d. The "distant" exchange operator extending the call to the "wanted" subscriber

The distant exchange operator having received 50 the number of the wanted subscriber will insert the calling plug of the connecting cord in use into the appropriate jack and provided that the wanted subscriber is not engaged the call will be extended in the normal manner and the calling subscriber notified that he is connected with the wanted subscriber by the printing of the letters "Thru" on his teleprinter, as described in paragraph 8.

What is claimed is:

- 55 1. In a telegraph exchange system a plurality of subscribers' stations each having a loop circuit through signalling apparatus and associated with a line jack serving for answering and calling the subscriber at a central station, a source of signalling current normally connected to both sides of each said loop circuit in parallel at the central station, means responsive to an earth condition on the loop circuit to indicate a calling condition from the subscriber, a cord circuit having an 60 answering plug and a calling plug, means operable on plugging in said calling plug to a line jack to connect said source in series in one direction with a wanted subscriber's loop, and means operable on plugging in said answering plug to 65 a calling subscriber's line jack following a calling

condition to connect said source in series in the other direction with the calling subscriber's loop.

70 2. In a telegraph exchange system a plurality of cord circuits at a central station for interconnecting any two subscribers' stations, a plurality of operators' positions less in number than said plurality of cord circuits, back-signalling means common to said plurality of operators' positions and adapted to transmit a series of code signals over a corresponding series of transmitting circuits, means individual to each cord circuit and responsive to the connection thereof to a required subscriber's line circuit to effect the operation of said back-signalling means, and means at the associated said operator's position responsive to the condition of the required subscriber's line circuit to complete a selective circuit from a corresponding one of the transmitting circuits of said back-signalling means to a calling subscriber through said cord circuit. 75

80 3. In a telegraph exchange system a plurality of cord circuits at a central station each cord circuit having a manually operable answering and calling plug, each plug being associated with a corresponding section of the cord circuit, back-signalling means adapted to transmit any one of a series of code signals, means responsive to the condition of a required subscriber's line circuit on connecting a calling plug thereto to effect the transmission to a calling subscriber through 85 the answering plug of a corresponding one of said series of code signals, and supervisory means individual to each cord circuit and operable on transmission of certain of said signals for identifying the cord circuit to which the said condition 90 applied. 95

4. In a telegraph system, a plurality of cord circuits at a central station for interconnecting any two subscribers' stations, back-signalling means adapted to transmit any one of a series of code signals, a supervisory relay individual to each cord circuit and operable on connection thereof to a required subscriber's line circuit to effect the connection of said back-signalling means to a calling subscriber's line circuit, other means 100 selectively responsive to the condition of the required subscriber's line circuit to effect the transmission by said back-signalling means of a corresponding one of said series of code signals to a calling subscriber, and supervisory lamp means 105 individual to each said cord circuit and operable upon transmission of certain of said series of code signals and upon receipt of a break signal from either subscriber's station notifying completion 110 of a call. 115

5. In a telegraph exchange system a plurality of cord circuits at a central station for interconnecting any two subscribers' stations, back-signalling means common to said plurality of cord circuits and adapted to transmit any one of a series 120 of code signals, a supervisory relay individual to each cord circuit and operable on connection thereof to a required subscriber's line circuit to effect the connection of said back-signalling means to a calling subscriber's line circuit, and other means selectively responsive to a "busy" or "disengaged" condition respectively of the required subscriber's line circuit to effect the transmission by said back-signalling means to the calling subscriber of one or other corresponding 125 130 one of said series of code signals.

6. In a telegraph exchange system, a plurality of cord circuits at a central station for interconnecting any two subscriber's stations, automatic back-signalling means connectible to any 135 140 145 150

- cord circuit during switching operations for interconnecting two said signalling stations and adapted to transmit to a calling subscriber code signals indicative of the condition of the required subscriber's line circuit, a supervisory lamp means individual to each said cord circuit and operable through said back-signalling means on the transmission of certain indications such as "busy" or "faulty" and in response to a clearing condition from either of said interconnected subscribers' stations notifying completion of a call. 10
7. In a central station for a telegraph exchange system a plurality of cord circuits, back-signalling means common thereto, means for causing said back signalling means to transmit any one of a series of signals over any one of said cord circuits, and supervisory signal means individual to each cord circuit and selectively controlled by said back signalling means for giving an indication to an operator. 15
8. In a central station for a telegraph exchange system a plurality of cord circuits, back-signalling means adapted to transmit any one of a plurality of code indications, and supervisory signal means individual to each cord circuit and operable by said back-signalling means for giving an indication to an operator following transmission of certain of said plurality of code indications. 20
9. In a telegraph exchange system a plurality of line jacks at a central station each jack serving for answering or calling a subscriber, back-signalling means, a plurality of cord circuits each having an answering and a calling plug, supervisory signal means individual to each cord circuit and controlled by said back-signalling means, means to render "busy" any said line jack, and separate bar alarm means common to said plurality of cord circuits operable on plugging a cord circuit into any said busy line jack. 25
10. In a control station for a telegraph exchange system a plurality of line jacks each multiplied to a number of operators' positions, a plurality of cord circuits each having an answering and a calling plug, means to associate a "busy" potential with a multiplied series of said line jacks, and separate bar alarm means common to said plurality of cord circuits and operable on plugging either jack of a cord circuit into any of said busy series of multiplied line jacks. 30
11. In a telegraph exchange system, a plurality of subscribers' stations, a corresponding plurality of line jacks at a central station, each jack serving to effect an answering or a calling connection with a said subscriber, a cord circuit at the central station and having an answering and a calling plug in each half section respectively of said cord circuit, a display equipment connectible to said answering plug and operable under control of dialling impulses from a calling subscriber, selective back-signalling means operable on connection of said calling plug to a required subscriber's line jack, and means controlled thereby to complete a circuit through said two sections of the cord circuit. 35
12. In a telegraph exchange system, a plurality of cord circuits at a central station each having an answering and a calling plug in each half section respectively, a display equipment common to said plurality of cord circuits and operable under the control of dialling impulses received over the answering half section of said plug. 40
13. In a telegraph exchange system, a subscriber's station having a loop circuit normally without current flowing therein, a central station having a connecting means in which said loop circuit terminates, a cord circuit, and a source of energy, means responsive to the initiation of a call by said subscriber's station for causing said source of energy to supply current in a normal direction to said loop circuit, means responsive to the interconnection of said cord circuit with said connecting means for causing said source of energy to supply current in the opposite direction to said loop circuit, and a printer at said subscriber's station adapted to be held inoperative when no current is flowing in the loop circuit and when the current flow in said loop circuit is in said normal direction and to be rendered operative when the current flow therein is in the opposite direction. 45
14. In a telegraph exchange system, a subscriber's station having a loop circuit normally without current flowing therein, a central station having a connecting means in which said loop circuit terminates, a cord circuit having an answering plug, and a source of energy, means responsive to the initiation of a call by said subscriber's station for causing said source of energy to supply current in a normal direction to said loop circuit, means responsive to the interconnection of said answering plug and said connecting means for causing said source of energy to supply current in the opposite direction to said loop circuit, and a printer at said subscriber's station adapted to be held inoperative when the current flow in said loop circuit is in said normal direction and to be rendered operative when the current flow therein is in the opposite direction. 50
15. In a telegraph exchange system, a subscriber's station having a loop circuit normally without current flowing therein, a polarized relay included in said loop circuit and adapted to hold said printer inoperative when the current flow in the loop circuit is in a normal direction but to render it operative when the current flow therein is in the opposite direction, a central station having a connecting means in which said loop circuit terminates, a cord circuit, and a source of energy, means responsive to the initiation of a call by said subscriber's station for causing said source of energy to supply current in a normal direction to said loop circuit, and means responsive to the interconnection of said cord circuit with said connecting means for causing said source of energy to supply current in the opposite direction to said loop circuit. 55
16. In a telegraph exchange system, a plurality of subscribers' stations each having a loop circuit normally without current flowing therein, a central station having a plurality of line jacks in each of which a loop circuit terminates, a plurality of cord circuits and a single source of potential, means responsive to the initiation of a call by a subscriber's station for causing said source of energy to supply current in a normal direction to the calling subscriber's loop circuit, means responsive to the interconnection of a cord circuit with the calling subscriber's line jack for causing said energy source to supply current in the opposite direction to the calling subscriber's loop circuit, and a printer at each subscriber's station adapted to be held inoperative when the current flow in the subscriber's loop circuit is in the normal direction and to be rendered operative when the current flow therein is in the opposite direction. 60

17. In a telegraph exchange system, a subscriber's station having a loop circuit normally without current flowing therein, a central station having a line jack in which said loop circuit terminates, a cord circuit, a source of energy, a first means, responsive to the initiation of a call by said subscriber's station, for causing said source of energy to supply current in a normal direction to said loop circuit, said relay means being also responsive to the connection of said cord circuit and said line jack to cause said source of energy to supply current in the opposite direction, and a printer at said subscriber's station adapted to be held inoperative when the current flow in said loop circuit is in the normal direction and to be rendered operative when the current flow is in the opposite direction.
18. In a telegraph exchange system, a sub-

scriber's station having a loop circuit normally without current flowing therein, a central station having a line jack in which said loop circuit terminates, a cord circuit, a source of energy, a first means, responsive to the initiation of a call by said subscriber's station, for causing said source of energy to supply current in a normal direction to said loop circuit, and a second means responsive to the connection of said cord circuit to said line jack when answering and calling said subscriber's station, for causing said source of energy to supply current in the opposite direction to said loop circuit, and a printer at said subscriber's station adapted to be held inoperative when the direction of current flow in said loop circuit is in the normal direction and to be rendered operative when the current flow therein is in the opposite direction.

RONALD GEORGE GRIFFITH.
